UNITED STATES PATENT OFFICE

165,827

CREAM PITCHER

R. Guy Cowan, Fayetteville, N. Y., assignor to
 Onondaga Pottery Company, Syracuse, N. Y., a
 corporation of New York

Application July 21, 1950, Serial No. 11,294

Term of patent 14 years

(Cl. D44—21)

To all whom it may concern:

Be it known that I, R. Guy Cowan, a citizen of the United States, residing at Fayetteville, county of Onondaga, State of New York, have invented a new, original, and ornamental Design for a Cream Pitcher, of which the following is a specification, reference being had to the accompanying drawing, forming a part hereof.

Figure 1 is a top plan view of a cream pitcher embodying my new design.

Figure 2 is a fragmentary sectional view taken on line 2—2 of Figure 3.

Figure 3 is a side elevational view.

Figure 4 is a fragmentary vertical sectional view taken on line 4—4 of Figure 1.

The dominant feature of the design consists in the relatively broad and shallow, spiral-fluted, exterior paneling terminating in and blending with smooth, unfluted surfaces near the top and bottom of the pitcher as shown.

I claim:

The ornamental design for a cream pitcher, as shown and described.

R. GUY COWAN.
